UNITED STATES PATENT OFFICE.

WILLIAM R. HUNTER, OF CHICAGO, ILLINOIS.

SPARK-PLUG.

1,288,898.

Specification of Letters Patent. Patented Dec. 24, 1918.

Application filed March 17, 1917. Serial No. 155,407.

To all whom it may concern:

Be it known that I, WILLIAM R. HUNTER, a citizen of the United States, residing at Chicago, in the county of Cook and State of

5 Illinois, have invented certain new and useful Improvements in Spark-Plugs, of which the following is a specification.

This invention relates to spark plugs for internal combustion engines and has for its 10 primary object the provision of a device of simple and relatively inexpensive construction embodying numerous advantageous features and designed particularly to permit relative changes of proportions between the 15 shell and core resulting from the different coefficients of expansion of the materials from which these parts are constructed.

A further object of my invention is the 20 provision of a spark plug so constructed that particles of carbon can not accumulate between the shell and the central electrode to short-circuit the plug.

Further objects and advantages of my invention will be apparent as it is better understood by reference to the following specification when read in connection with the accompanying drawing illustrating the preferred embodiment thereof, in which—

Figure 1 is a longitudinal section through 30 a spark plug according to my invention;

Fig. 2 is a plan view of the electrode end of the plug, and

Figs. 3 to 9, inclusive, are details in perspective of the various parts of the plug, 35 some of the figures being in section to better illustrate the construction.

Referring to the drawing, 5 indicates a metal shell threaded at 6 in the usual manner and provided with an internal flange 7. 40 Mounted within the shell on opposite sides of the flange 7 are sections 8 and 9 of an insulating core, preferably of vitreous material. Washers 10 of asbestos or other suitable material are disposed between the sides 45 of the flange 7 and the contiguous ends of the sections 8 and 9. The section 9 is provided at its inner end with a recess 11 to receive the reduced portion 12 of the section 8.

50 A central electrode 13, having a flattened end 14 and a flange 15, passes through the sections 8 and 9 of the core and is threaded at its opposite end to receive the nuts 16 and 17. A split or spring washer 18 is disposed 55 between the lower nut 16 and the section 9 of the core. When the parts are in assembled

relation the sections 8 and 9 of the core are resiliently clamped together by the electrode 13 and its coöperating washer and nuts and the core is maintained within the shell by 60 the engagement of the ends of the sections 8 and 9 with the flange 7.

The diameter of the sections 8 and 9 is sufficiently less than the inner diameter of the shell 5 to permit free lateral expansion 65 of the sections of the core and inasmuch as the core engages the shell only at the flange 7 and through the resilient washers 10 it is apparent that free longitudinal expansion of the sections of the core with reference 70 to the shell is possible. The resiliency of the washers 10 and the spring washer 18 permits expansion of the sections 8 and 9 with respect to the electrode 13. The tendency of the vitreous insulating core to crack 75 under the strains set up by the relative changes in proportions resulting from the different coefficients of expansion of the materials constituting the plug is entirely overcome by the above-described construction. 80 As will be readily understood the shell and core are free to expand and contract with reference to each other while the parts are still maintained in rigid assembled relation as is essential to the continued successful op- 85 eration of the device.

An electrode 19 is secured to one end of the shell 5 in coöperative relation to the flattened end 14 of the electrode 13. The edge of the flattened end 14 is disposed in parallel 90 relation to the end of the electrode 19 so that when the device is in use a spark of considerable area will be produced. To overcome the usual tendency of spark plugs to become foul with carbon, which eventually 95 bridges the space between the shell and central electrode and short-circuits the plug, the section 8 is extended beyond the end of the shell 5 as indicated at 20 and a recess 21 is formed in the end of the section through 100 which the electrode 13 extends. By this construction the central electrode is separated from the shell by a wall or partition which effectively prevents the formation of a carbon bridge between the parts and thus the 105 danger of short-circuiting the plug is eliminated.

It will be readily understood that various changes may be made in the form, construction and arrangement of the parts without departing from the spirit and scope of the invention or sacrificing any of its mate-

rial advantages, the form hereinbefore described being merely a preferred embodiment thereof.

I claim:

- 5 In a spark plug the combination of a conducting shell having an interior flange, an insulating core consisting of upper and lower sections, the contiguous ends of which bear against said flange, said lower section 10 being substantially equal in diameter to the internal diameter of said shell and having a sloping shoulder engaging said flange and a

shallow central recess of relatively large diameter in its lower end, a central electrode projecting through said recess and provided 15 with a flattened end, means on said electrode to hold said sections in assembled relation, and an electrode on said shell cooperating with the flattened end of said central electrode.

WILLIAM R. HUNTER.
